UNITED STATES PATENT OFFICE

165,965

FLOW GAUGE

Frederick K. Daniel, Kew Gardens, N. Y.

Application August 16, 1950, Serial No. 11,782

Term of patent 3½ years

(Cl. D52—1)

To all whom it may concern:

Be it known that I, Frederick K. Daniel, a citizen of the United States and a resident of Kew Gardens, county of Queen and State of New York, have invented a new, original, and ornamental Design for a Flow Gauge, of which the following is a specification, reference being had to the accompanying drawings, forming part hereof, and in which:

Fig. 1 is a top perspective view of the flow gauge, showing my new design.

Fig. 2 is a top plan view.

Fig. 3 is a side elevational view.

I claim:

The ornamental design for a flow gauge, as shown.

FREDERICK K. DANIEL.
